CLAIM

The ornamental design for a wine rack, as shown and described.

DESCRIPTION

FIG. 1 is a top view of my new design for a wine rack;
FIG. 2 is a left side view thereof;
FIG. 3 is a front view thereof;
FIG. 4 is a right side view thereof;
FIG. 5 is a back view thereof;
FIG. 6 is a bottom view thereof;
FIG. 7 is a front and top-down perspective view thereof;
FIG. 8 is a front and bottom-up perspective view thereof;
and,
FIG. 9 is a rear and top-down perspective view thereof.
The broken lines shown in the drawings are for the purpose of illustrating portions of the wine rack that form no part of the claimed design.
